WEDDING PLACE CARD HOLDER

William Taylor Jones, Scranton, Pa., assignor to Consolidated Molded Products Corporation, Scranton, Pa., a corporation of Delaware

Application November 10, 1955, Serial No. 38,831

Term of patent 14 years

(Cl. D1—3)

Fig. 1 is a plan view of the wedding place card holder embodying the design; and

Fig. 2 is a front elevational view of the place card holder.

The card, shown in dotted lines, is for purposes of illustration only.

I claim:

The ornamental design for a wedding place card holder, as shown and described.
